UNITED STATES PATENT OFFICE.

JOSEPH R. KLUMP, OF CHICAGO, ILLINOIS, ASSIGNOR TO INTERSTATE IRON AND STEEL COMPANY, OF CHICAGO, ILLINOIS, A CORPORATION OF ILLINOIS.

COOLING BED.

Application filed March 23, 1922. Serial No. 545,944.

To all whom it may concern:

Be it known that I, JOSEPH RICHARD KLUMP, a citizen of the United States, residing at Chicago, in the county of Cook, State of Illinois, having invented certain new and useful Improvements in Cooling Beds, do hereby declare that the following is a full, clear, and exact description of the same.

10 My invention relates to cooling beds used in handling hot metal bars as they are delivered from the reducing-rolls of a rolling-mill, and consists in the novel and useful constructions herein described and then 15 pointed out in the appended claims.

In the accompanying drawings which illustrate a practical embodiment of the features of my invention and in which the same reference numerals indicate similar 20 parts in the different views, Fig. 1 is a top plan view of a longitudinal portion of a cooling bed of well-known construction and operation equipped with my invention, the discharge end of the horizontal section of 25 the bed and the bars under treatment being shown as broken-away for convenience of illustration; Fig. 2 is a detail vertical sectional view on the line 2—2 in Fig. 1 with the parts in their positions when no bars are 30 passing from the inclined section of the bed to its horizontal section; Figs. 3 and 4 are similar views showing parts in various positions when bars are passing over the bed, Fig. 5 is a detail view of a part of the rack 35 and guide, and Fig. 6 is a detail view.

The object of my invention is to provide an improved guide for the bars as they pass from the inclined gravity section of the bed to the initial pocket of the horizontal section, and one that is particularly adapted for use when the bed is handling flat stock in packs to permit the annealing on the bed of material of small cross-section, such as flat spring stock, which would otherwise cool too fast on the bed to pass the required specifications unless it were annealed later.

Referring to the accompanying drawings which show my invention the reference letter A designates a long trough or runoff table provided with a series of feed-rolls a which project through openings into the trough and convey the metal bar as it is delivered from the reducing-rolls. In practice the trough is usually long enough to

accommodate a 300 foot bar, and the cooling bed, of whose length only a section is shown, is correspondingly extended.

The skid-section B of the bed includes a series of rigid inclined skid-beams B' upon which the bars α are delivered from the trough. Between the beams B' are journaled in the bed a series of rocking-shafts C parallel with the beams and having arms C', C² and C³ extending therefrom; the arms C' on the ends of the shafts are arranged to pass through open-end slots α' in the trough A so that upon oscillation of the shafts they will transfer the bar out of the trough to the bed, and the other arms are arranged in staggered relation on opposite sides of each shaft and extend radially to project alternately into vertical position to form escapement stops or dogs above the skids as the shafts are oscillated, the corresponding dogs of the shafts being arranged in a straight row extending longitudinally of the bed so that the hot metal bars α will be preserved in straight lines. Suitable mechanism which is well-known and forms no part of my present invention, and so need not be here shown and described, actuates the rocking-shafts so that they are simultaneously rocked back and forth to allow the bars lying on the skids to move by gravity successively down them from one row of dogs to the next lower row until they pass one by one from the last row upon the inclined guides B² at the lower end of the skid-section B by which they are delivered to the front or leading pocket of the horizontal section of the cooling bed. The skid-beams may have vertical ribs b in staggered relation.

The rack-section of the cooling bed is composed of a series of parallel horizontal racks D arranged respectively in line with the skid-beams as shown in Fig. 1. Each rack unit is composed of a base d and marginal vertical webs d' provided with a series of troughs or pockets D' which are V-shaped in cross-section, the corresponding pockets of the racks being arranged in straight lines. The faces of the pockets may have vertical ribs d² in staggered relation. Suitable mechanism of well-known construction, designated generally at D², may be employed to lift and move the bars from each pocket and deposit them in the next one and discharge them upon the assembly.

table (not shown), and when the bars are to be arranged in packs x' the inclined guides B^2 will be formed as jointed arms and the lower arms will be actuated from below to oscillate to different positions in relation to the leading faces of the initial pockets as shown in the drawings as now well-understood to form packing-mechanism to deliver the bars from the skid-section of the bed to the first row of pockets in the rack-section so that they will be disposed therein in a pack as shown at x' ; mechanisms for both these purposes are now well-known and form no part of my invention and so need not be here described in detail. The lower arms B^2 may be actuated by links B^3 pivoted thereto and to crank-arms B^4 fixed on an operating shaft B^5 as shown in Fig. 6, the length of the stroke of the arms being controlled by the operator.

Arranged above the bed at spaced intervals are a plurality of stock guides E ; each consists of an elongated curved spring arm attached at one end to the outer portion of the trough A and extending thence above one of the skids B' in an upwardly curved contour and having its free or outer end disposed between the webs d' of the corresponding rack D of the horizontal section. In practice the guides are formed of flat strips of spring-metal, about two (2) inches wide, and the free end e of each extends above the top line of the webs and thence inwardly in a line tangential to the plane of the inner or leading face of the first notch or pocket of the rack; the end of the guide is approximately in this plane and its under face gradually departs outwardly from this plane and forms an upwardly opening or flared mouth between its end and the leading face of the initial pocket as shown in Fig. 2 when the bars are handled singly, and also between its end and the movable arm of the packing-device B^2 as shown in Fig. 3 when the bars are being accumulated in a pack. By this construction the guide contacts with the bar only at its leading point as the latter moves into the first pocket or notch of the horizontal section of the bed. The tips e' of the guides are curved outwardly to allow the bars to more easily wipe past them in passing out of the pockets. The guides are located at suitable points along the length of the bed, being spaced apart longitudinally thereof at such distances as the length of the bars requires; if desired a guide may be provided at each rack D .

When the bars pass from the inclined section of the bed to the horizontal section they move under the guides E , which hold them from turning and ensure their uniform emplacement in the initial notch or pocket of the racks. This feature is advantageous when the bars are handled singly as the

guides prevent them from unevenly passing down the inner or leading faces of the first notches at different points in their length and so hold them against any twisting or deforming action that would then occur, especially in bars of considerable length. It is especially advantageous when the cooling bed is handling flat stock in packs as it prevents the flat bars from turning and also ensures their being seated with uniform motion so that all are properly positioned and aligned in the pack; as shown at x' in Fig. 3 all the bars are guided edgewise into the pack. When handling flat stock or bars, such for example as spring steel or other material of small cross-section, it is desirable to cool them in packs as this permits the annealing of the material; the heat from the center of the pack anneals its surfaces, it being understood that the critical temperature for properly annealing the material is reached by the time the pack is lifted from the third row of pockets of the racks. To successfully anneal the pack in the bed it is desirable to minimize the extent of their contact with colder metal therein and so prevent the latter from drawing the heat from these portions of the bars faster than the heat from the other portions of the pack can evenly anneal them. By locating the guides E between the webs of the racks these parts are offset in the direction of travel of the bars so that any portions of the bars that may be chilled by them are out of line and will be reheated to the temperature of the other parts of the pack by the exchange of heat by conduction from the large non-chilled portion to the small chilled portion. As the guides seat the bars edgewise they are valuable in packing or accumulating them in the first notch of the horizontal portion of the bed in an arrangement that secures uniformity in packing and permits the annealing of the material in the bed, and the tangential relation of the end of the guide to the leading face of the notch so that it touches each bar only at its leading point and in a restricted area limited to a transverse line or edge e of the guide reduces the chilling action of the guide itself to a minimum; the contact of the guides with each succeeding bar of the pack is negligible in chilling effect.

When the machine is handling either single bars or packs the transfer mechanism lifts and carries the material forward from notch to notch in the horizontal section of the bed and then discharges it upon a suitable assembly table (not shown), and as the material is carried out of the first notch the free ends of the guides are raised and the material wipes past them as shown in Fig. 4, the shape of the tips of the guides permitting a single bar to pass without turning it and permitting a pack to pass without dis-

turbing the upper bar thereof. After the material clears the guides they spring back into their normal positions.

I claim:

- 5 1. In a cooling bed, an inclined skid-section, a horizontal rack-section having a series of pockets arranged in rows along its length, and a guide located at the initial pocket of each of a plurality of the racks 10 and constructed to restrain the stock from turning as it passes from the skid-section to the rack-section.
- 15 2. In a cooling bed, an inclined skid-section, a horizontal rack-section having a series of pockets arranged in rows along its length, packing-mechanism between the sections, and a guide located at the initial pocket of each of a plurality of the racks and constructed to restrain the stock from 20 turning as it passes from the skid-section and the packing-mechanism to the rack-section.
- 20 3. In a cooling bed, an inclined skid, a

horizontal rack having spaced vertical webs provided with a series of pockets, and a 25 stock-guide consisting of a spring-metal strip secured at one end to the bed and extending above the line of the webs and terminating at its free end between the webs at the initial pocket of the rack.

30 4. In a cooling bed, an inclined skid, a horizontal rack having vertical webs provided with a series of V-shaped pockets, and a stock-guide consisting of a spring-metal strip mounted on the bed and having its free 35 end tangential to the plane of the leading face of the initial pocket of the rack.

5. In a cooling bed, an inclined skid, a horizontal rack having a series of V-shaped pockets, and a stock-guide at the initial 40 pocket of the rack constructed to form a flared mouth with the leading face of the pocket and having its tip curved away from said face.

In testimony whereof I affix my signature.
JOSEPH R. KLUMP.
